UNITED STATES PATENT OFFICE.

THOMAS HICKS, JR., OF GRAVESEND, NEW YORK.

MILLINER'S STEAMER AND PRESSER.

SPECIFICATION forming part of Letters Patent No. 232,716, dated September 28, 1880.

Application filed April 17, 1880. (No model.)

To all whom it may concern:

Be it known that I, THOMAS HICKS, Jr., of Gravesend, in the county of Kings and State of New York, have invented a new and Improved 5 Milliner's Steamer and Presser, of which the following is a specification.

This invention relates to that class of devices designed for milliner's use for the purpose of raising the pile on velvets, &c., and 10 will first be described in connection with the drawings, and then pointed out in the claims.

Figure 1 is a plan of the device with the cloth removed and a portion broken away the better to exhibit other parts. Fig. 2 is a side 15 elevation of the same, partly in section, on line xx , Fig. 1. Fig. 3 is a cross-section of a portion of the device on line yy , Fig. 1, and Fig. 4 is a front elevation.

Similar letters of reference indicate corresponding parts in all the figures.

In the drawings, A is a box or case, in which a water-reservoir, B, is formed by means of the vertical partition C. D is the movable front of the box, provided with the vertical slot a . 25 E E are the lamps—attached, if desirable, to the movable front D—placed within the box or case A, on either side thereof, leaving a longitudinal space between them for the reception of the handle c of the flat-iron F, and about 30 the wicks of these lamps E are the chimneys b, which direct the heat and flame upward against the said flat-iron F, and are designed also to prevent the heating of the handle of the said flat-iron, which handle c projects down between them. The wicks of these lamps are 35 adjusted by the regulators d, that extend from the front of the device, and air is admitted to the wicks through the side openings, o o.

A roller-frame, G, composed of two side 40 bars, f f, that carry at their forward ends a roller, g, is hinged on pins h, which pins extend laterally from the rear of the device, about opposite the partition C, and the side strips, f f, of said frame G are slightly bent inward, 45 so that they may rest upon the upper edges of the box A below the level of the flat-iron face and be thereby supported.

A strip of cloth, H, is wound around the roller I, which is revolved by means of the 50 crank m in the water K within the reservoir B, and said strip H is passed up between the rollers L L and over the face of the flat-iron F, and made fast to the roller g of the frame G,

which roller g projects over the front of the device.

In operating this device the lamps E E are lighted and allowed to burn until the face of the flat-iron F is sufficiently heated, the frame G, with the cloth attached, being thrown back at the same time in the position indicated by dotted lines, Fig. 2, or being altogether disengaged from the apparatus; then, when the flat-iron F is sufficiently heated, the frame G, with its attached cloth H, is turned down over the face of the flat-iron F in the position shown in Figs. 1 and 2. The roller g is then turned so as to draw the cloth H from the roller I up between the rollers L L, which rollers L L may also be revolved by means of a crank, or by the cloth that is drawn upward between them and over the flat-iron F, the rollers L L serving to squeeze any excess of water out of the said cloth H. Immediately then the heat of the flat-iron causes steam to arise from the cloth H, which is over the face of the said flat-iron F, and the operator then taking the piece of velvet or other material to be operated upon draws it, with downward pressure, slowly and transversely over and upon the said steaming-cloth H, and thereby effects the steaming. On lifting the frame G the said flat-iron F can be withdrawn through the said slot a of the front D, and be used after the manner of the ordinary flat-iron, and thus accomplish the pressing.

Having thus described my invention, I claim as new and desire to secure by Letters Patent—

1. A steamer and presser consisting of the box A, having water-reservoir B, lamps E E, flat-iron F, roller-frame G, cloth strip H, and rollers I L, as shown and described.

2. In a steamer and presser, the combination, with the box or case provided with the water-reservoir B, of the hinged roller-frame G, the cloth strip H, and rollers I L, substantially as herein shown and described.

3. In a steamer and presser, the combination, with the box or case A and flat-iron F, of the hinged roller-frame G and cloth strip H, substantially as herein shown and described.

THOMAS HICKS, JR.
